George Arras,

By Kent W. Howell atty.

UNITED STATES PATENT OFFICE

GEORGE ARRAS, OF CHICAGO, ILLINOIS

FIXTURE SUPPORT

Application filed October 20, 1928. Serial No. 313,704.

This invention relates in general to a fixture support and has more particular reference to a globe and shade fastener for electric fixtures, although it may have a more general application wherever applicable.

One of the principal objects of the invention is to provide means for attaching a shade or globe to a support in a simple effective manner. A further object of the invention is the provision of means for positioning a shade or globe in a given direction or location by the act of fastening it in place.

15 Further objects of the invention will appear hereinafter, the drawing illustrating a preferred embodiment of the invention.

In the drawing:

Figure 1 is a side elevation of a fixture support and a reflector in accordance with the invention;

Figure 2 is a sectional view of the fixture parts shown in Figure 1;

Figure 3 is a view of the attachment end 25 of a globe or shade; and

Figure 4 is a sectional view taken on the line 4—4 of Figure 2.

This invention provides a simple means for attaching a shade or globe to a fitting 30 at the end of a conduit or to the lid of a conduit box by providing an electric lamp socket which is inserted through an opening in the base of the shade, and these parts then relatively rotated and the socket attached to its support which clamps the shade 35 between the socket and its support.

In practice the socket is usually attached loosely to the support by fastening screws or the like, the shade or globe is inserted 40 over the socket and rotated substantially ninety degrees and the socket then secured tightly in place, thereby clamping the shade in its intended place at the same time.

Referring more particularly to the drawing, a socket 5 for receiving an electric lamp 45 6 has opposite projections 7, the central portions of which are recessed on opposite sides and provided with a perforation 8 for receiving a fastening screw 9. At the side 50 opposite the head of the screw is a washer

10 for holding it in place, the head being seated in the recess at one end of the projection.

This socket is attached by means of the screws 9 to any suitable support, such for example as a supporting head 11 threaded onto the end of a conduit 12 through which extend electric wires 13 for the socket. This head 11 may be circular in form, as shown in Figures 1 and 2 or the conduit outlet may be at one side of a fitting 11^a for receiving a conduit 12^a at right angles to the circular end, as shown in dotted outline in Figure 1, and the circular end of either form is usually provided with an overhanging flange 14 for receiving the end of a globe or shade.

A shade or globe of any size or shape may be applied to the fixture as for example an angle reflector 15, as shown in Figure 1, 70 but the attachment shell 16 is reduced at its end to fit within the circular flange 14, and the end or bottom of this reduced portion has a shaped opening 17 adapted to fit more or less loosely over the socket 5 75 so that the socket may be passed through the opening in the end of the shade. At opposite sides of the opening 17 are notches or extensions 18 having one radial portion and a curved portion extending from the outer end of the radial portion such that the screws 9 of the socket are located in the notches 18 in contact with the radial portions thereof when the socket and shade are relatively rotated approximately a quarter 80 turn or ninety degrees, bringing the remaining portions or loops 19 of the end of the shade between the socket and the support to which it is attached, and when the screws are tightened securely clamping the 85 shade between the socket and the support 11, and holding the shade in this position until the screws are released.

This construction is particularly valuable in locating or positioning a number of 90 shades or reflectors so that they will extend and remain in a certain direction. For example, a number of angle reflectors such as shown in Figure 1 are to be directed toward a bill board. It is necessary only 100

to set the lamp sockets in the proper direction at the ends of the conduits by means of the threaded connections between the parts and then when the shade or reflector 5 is applied, it is inserted over the socket at ninety degrees to the position desired, rotated to the proper position, and fastened in place by the socket screws.

This invention may be applied in a great 10 variety of ways to fixtures of various kinds and has particular application to globes and shades for electrical fixtures. The term shade is intended to cover reflectors, globes, plates and canopies.

15 I claim:

1. The combination with a fixture support; of a socket having fastening means to secure it to the support; and a shade having an opening in its base insertable over the 20 socket, and rotatable to directly engage the base between the socket and its support.

2. The combination with a support, of a socket having fastening means to attach it to the support, and a shade having a corresponding perforation in its base through which the socket will pass when they register, and having portions engaged between the socket and the support when the shade is rotated, the fastening means being adapted to secure the shade directly therebetween. 30

3. The combination with a support, of a socket having side extensions with fastening means therethrough for attaching it to the support, and a shade having a perforation in its base to admit the socket therethrough and rotatable to directly and positively engage portions of the base between the side extensions and the support, the fastening means securing the shade in place. 35

4. The combination with a support, of a member having opposite projections with fastening means inserted therethrough for attaching it to the support, and a shade having a perforated base to admit the member therethrough and with a notch in the perforation to engage the fastening means when the shade is applied between the member and the support to limit the rotation thereof. 45

5. The combination of a lamp socket, and a shade therefor, the socket having side projections with fastening means extending therethrough, and the shade having an opening to admit the socket and its projections therethrough, the opening having a projection to engage one of the fastening means when the shade is applied over the socket and rotated, to limit the rotation thereof. 55

6. The combination with a lamp socket 60 having side projections with fastening screws inserted therethrough, of a shade having a base with a perforation through which the socket and its projections will pass closely, the base having notches at the 65 sides of the perforation to engage the screws

and limit the relative rotation of the shade and socket when the shade is applied thereon.

7. The combination with a support, of a lamp shade adapted to be set in a predetermined angular position with respect thereto, and a lamp socket having fastening means for attaching it to the support, the shade having an opening to closely admit the socket therethrough and thereupon rotatable to engage the base at the edge of the opening between the socket and its support before the socket is secured thereto, the edge of the opening being formed with a notch to engage the fastening means when the shade is rotated to limit this relative movement and to position the shade at the predetermined angular position with respect to the support. 75 80

8. In a fixture support, a lamp socket having side projections with fastening screws therethrough, and a shade having a perforation through which the socket and its projections pass closely, the shade having notches at the sides adapted to engage the screws when applied to the socket and to limit the relative rotary movement of the shade and socket to ninety degrees. 85 90

9. A fixture support comprising a shade having an opening through which a socket is adapted to extend, the edges of the opening being clamped directly between a socket and its support, and the opening having side notches which engage a socket fastening means to limit the rotation thereof. 95 100

10. A fixture support comprising a shade having a base opening which closely admits a lamp socket with lateral projections therethrough, the opening having opposite notches to engage fastening means inserted through the projections and limiting the relative rotation of a socket and a shade applied thereto to a position at right angles to that at which a lamp socket is inserted through the opening. 105 110
